UNITED STATES PATENT OFFICE.

ARTHUR D. McPHERSON, OF OAK PARK, ILLINOIS.

ATTACHING-HANGER FOR ELEVATOR-BUCKETS.

1,210,662.

Specification of Letters Patent.

Patented Jan. 2, 1917.

Application filed December 30, 1915. Serial No. 69,310.

To all whom it may concern:

Be it known that I, ARTHUR D. McPHERSON, a citizen of the United States, residing at Oak Park, in the county of Cook and State of Illinois have invented certain new and useful Improvements in Attaching-Hangers for Elevator-Buckets, of which the following is a specification.

My invention relates to attaching hangers for securing buckets or cups to elevator belts.

One of the objects of my invention is to provide a hanger or bracket whereby to attach elevator buckets to conveyer belts to thereby project the discharge edge of such bucket laterally from the belt so that the spill from said bucket will be discharged farther from the vertical path of the belt so that the bucket content may pass out through the discharge opening of the conveyer head, and not through the adjacent leg into the boot below, as with buckets of usual construction attached directly to the belt in the ordinary manner.

Another object of my invention is to provide a hanger or bracket that may be used with the ordinary type of conveyer bucket to secure them to belts, whereby to realize all of the beneficial results arising from my manner of securing buckets to belts. And still another object of my invention is to provide a hanger that will secure the desired result without decreasing the capacity of the bucket to any appreciable extent.

Other and further objects of my invention will become readily apparent to persons skilled in the art, from a consideration of the following description when taken in conjunction with the drawings, wherein:

Figure 1 is a central section taken through a typical elevator, such as used in flour mills, showing an elevator head and fragments of two depending legs. Fig. 2 is an enlarged central section, taken through the belt and one hanger and bucket. Fig. 3 is a perspective isometric view of a bucket of the usual type and my hanger attached thereto.

In all the views the same reference characters are employed to indicate similar parts.

5 is a conveyer head showing depending legs 6 and 7, and a discharge opening 8.

9 is a conveyer belt passing over the pulley 10 and having secured thereto the ordinary type of conveyer bucket 11 by means

of my improved hanger 12. The bucket 11 is of the ordinary type but the discharge edge 14 is farther removed laterally from the belt than customary, as when the bucket 60 is attached directly to the belt in the usual manner.

My hanger consists preferably of a piece of sheet metal of width substantially equal to the length of the bucket. It is bent upon 65 itself at rather an acute angle, as at 15, to provide a slanting surface 16 so that any material that may be lodged upon this surface will be precipitated into the interior of the bucket. It is bent again, as at 17, to 70 provide a flange, which is designed to be secured to the inside surface of the rear wall of the bucket, or to the outside surface thereof as desired, preferably, by electrically spot welding the surfaces together or by 75 means of countersunk rivets, as desired. The welding spots 18 I show clearly in Fig. 3. A longer member 19 of the hanger is adapted to extend back of the bucket in substantial contact with the belt 9 and is perforated 80 for attaching bolts 20, of which there may be any desired number, that takes through the belt and through said perforations and other perforations to be provided in the belt. The back member 19 extends 85 to a point 21, about where the bottom of the bucket begins to curve, and at this point it may be welded, or otherwise secured to the back wall of the bucket.

In applying my hanger at the elevators, 90 in which the buckets are already in use, I prefer to rivet the hanger to the bucket, but where they are made initially in the shop and shipped to the elevator, it is more convenient and less expensive to spot weld the 95 parts together in the manner described. The manner of attachment does not form any part of my invention and therefore any convenient means of attaching the hanger to the bucket, and to the belt, may be employed.

When the bucket is supported on the conveyer belt by means of my hanger the spill 92, as shown in Fig. 1, is projected or shed clear and clean from the bucket toward and 105 through the opening 8 provided in the elevator head and is not discharged into the vertical leg 6, as usual when such buckets are attached directly to the conveyer belts in the manner generally employed.

My hanger, being secured at each end to the elevator bucket in the manner shown

provides a rigid brace which very greatly reinforces and strengthens that portion of the bucket that is called upon to sustain the load and take the wear, consequently it prolongs the useful life of the bucket. The hanger being a part separable from the bucket and lying substantially without the interior thereof, the capacity of the bucket is not decreased or curtailed by its use. The longer rear member of the hanger is curved to correspond with the rim of the pulley so that the rear end of the bucket will lie close to the belt and the forward end will project as far as may be therefrom.

15 While I have herein shown a single embodiment of my invention for the purpose of clear disclosure, my invention is limited only by the scope of the appended claim.

Having described my invention, what I claim is:

20 The combination with an elevator belt and

bucket of a sheet metal hanger therefor comprising an upper edge portion adapted to engage an edge of the bucket, means for securing the bucket edge to the edge portion of the hanger, a portion extending outwardly from the bucket edge and then downwardly and inwardly for coöperation with the outer surface of the bucket near the bottom thereof, means for securing the lower edge of the downwardly and inwardly extending portion of the hanger to the bucket, and means for securing the downwardly and inwardly projecting portion of the hanger intermediate its end to the belt. 25 30 35

In testimony whereof I hereunto set my hand in the presence of two subscribing witnesses.

ARTHUR D. McPHERSON.

In the presence of—

FORÉE BAIN,

MARY F. ALLEN.
